UNITED STATES PATENT OFFICE.

JAMES J. SHERIDAN, OF ELIZABETH, NEW JERSEY, AND EDMUND S. STEVENS, OF WEST PITTSTON, PENNSYLVANIA.

STRIP-MARKER.

1,263,134.

Specification of Letters Patent.

Patented Apr. 16, 1918.

Application filed February 5, 1914, Serial No. 816,743. Renewed March 4, 1918. Serial No. 220,380.

To all whom it may concern:

Be it known that we, JAMES J. SHERIDAN and EDMUND S. STEVENS, citizens of the United States, said SHERIDAN residing at 5 Elizabeth, county of Union, and State of New Jersey, and said STEVENS residing at West Pittston, Luzerne Co., and State of Pa., have invented certain new and useful Improvements in Strip-Markers, of which the 10 following is a specification.

The invention relates to such improvements and consists in the novel construction and combination of parts hereinafter described and subsequently claimed.

15 Reference may be had to the accompanying drawings, and the reference characters marked thereon, which form a part of this specification. Similar characters refer to similar parts in the several figures therein.

20 Figure 1 of the drawings is a view in elevation of one side of our improved strip-marker.

Fig. 2 is a view in elevation of the opposite side thereof.

25 Fig. 3 is an end view in elevation of one of the segments of the expandable and contractible drum.

Fig. 4 is a central longitudinal section of the same.

30 Fig. 5 is a view in side elevation of one of the slotted end-disks, whereby the sections of the drum are guided in their inward and outward movements, which disk also serves as a cam for operating the marking pencil.

35 Fig. 6 is a view in front elevation of the device as shown in Fig. 1.

Fig. 7 is a central vertical section taken through the axis of the expandable and contractible drum showing the same removed 40 from its bearing-support.

Fig. 8 is a transverse section of the same taken on the broken line 8—8 in Fig. 7.

Fig. 9 is a view in side elevation of the size-indicating wheel detached.

45 Fig. 10 is a vertical cross-section taken on the broken line 10—10 in Fig. 1, showing the manner in which the pencil-support is adjustable for different sizes of drum.

The principal object of our invention is 50 to automatically apply to a strip of flexible material marks at regular predetermined intervals, indicating points at which the strip can be severed to form sections of equal lengths adapted for various uses.

55 The apparatus shown in the drawings is

particularly adapted for thus marking a strip, sections of which are to be severed or stitched upon underdrawers to form waistbands therefor.

In carrying out our invention, we employ 60 an ordinary crayon or lead-pencil in combination with a drum over which the strip is fed, with means for supporting the pencil and causing it to engage the strip at each rotation of the drum, provision being made 65 for varying the diameter of the drum in accordance with the length of the sections to be cut from the strip, and for adapting the position of the pencil to the size of the drum.

Referring to the drawings wherein the invention is shown in preferred form, 1 is a standard having an upwardly extending yoke-bearing, 2, for the tape-measuring drum.

Upon the body of the standard is rotatively mounted a reel, 3, which carries a supply of tape or binding strip, 4, which strip passes from the reel over the drum, thence to a guide, 5, from which it may be passed directly to a sewing-machine, not 80 shown, or to the operator, or elsewhere as may be desired.

The drum is made up of a plurality of segments, 6, each of which has end-portions, 7, fitting and movable along oppositely located radial slots, 8, in the end-disks, 9, which end-disks are riveted upon a sleeve, 10, whereby they are supported in fixed relation to each other.

The sleeve, 10, is rotatively mounted upon 90 a sleeve, 11, upon one end of which sleeve, 11, is fixedly mounted a cam-disk, 12.

A similar cam-disk, 13, is mounted upon the other end of the sleeve, 11, by means of a feather, 14, Fig. 7, whereby the two cam-disks are adapted to rotate in unison with each other, while capable of a slight relative movement toward or from each other.

A nut, 15, fits a screw-threaded portion of the sleeve, 11, and serves as a clamping 100 means for forcing the cam-disk, 13, toward the cam-disk, 12, to clamp between said cam-disks and in fixed relation thereto the segment-supporting disks, 9, of the drum, thus causing the drum, the cam-disks, 12 and 13, 105 and the sleeves 10 and 11, to all rotate together.

The sleeve, 11, is mounted upon a shaft, 16, which shaft is mounted in bearings in the yoke-frame, 2.

The inner faces of the cam-disks, 12 and 13, are formed with corresponding cam-grooves, 17, each of which cam-grooves is preferably in the form of a continuous spiral 5 extending several times around the circular extent of the disk, the groove so formed receding very gradually from the center of the drum.

The slots, 8, are equidistant from each 10 other, and each of the segments has on its opposite ends projections preferably formed by screws, 18, the heads of which are adapted to enter the respective spiral grooves, 17, and form cam-followers.

15 The screws, 18, are so located upon the respective segments, 6, that while the screws of the various segments occupy portions of the grooves, 17, at different distances from the axis of the drum, the strip-engaging surfaces 20 of the various segments are located in a common circle concentric with the drum.

By loosening the nut, 15, and holding one of the slotted end-disks, 9, by hand against rotation and rotating the cam-disk, 13, 25 which carries with it the cam-disk, 12, the segment-screws, 18, can be caused to travel toward or from the axis of the drum as the case may be, whereby the segments, 6, are moved inward or outward to change the 30 diameter of the drum.

When the drum has been thus adjusted to the proper diameter, the end-disks, 9, and cam-disks, 12 and 13, are clamped tightly together by means of the nut, 15, to prevent 35 accidental variation in the diameter of the drum.

For marking the tape at the proper intervals, we employ an ordinary crayon or lead-pencil, 20, attached by means of an adjustable clamp, 21, to a bracket, 22, which overhangs the drum and which is mounted upon the upper end of a slide, 23, which slide is vertically movable in a slideway, 24, on one of the arms of the bearing-yoke, 2.

45 A coil-spring, 25, engages an angular foot, 26, of the slide, 23, tending to depress the slide and force the pencil, 20, against the drum or interposed strip.

A cam-follower, 27, carried by the bracket, 50 22, engages a cam-flange, 28, on the neighboring slotted disk, 9, being adapted to enter a notch, 30, in said cam-flange at each rotation of the drum. Except at the notch, 30, the cam-flange, 28, is of sufficient height 55 to withhold the pencil, 20, from contact with the drum or strip.

In adapting the pencil for different sizes of drum, the pencil may be directly adjusted by means of the clamp, 21, so that the pencil 60 will properly engage the strip upon the drum when the cam-follower, 27, occupies the notch, 30.

We prefer, however, to accomplish this 65 adjustment by changing the elevation of the follower, 27, relatively to the point of

the pencil, for which purpose we have shown the follower, 27, mounted upon a spindle, 31, formed with a series of openings, 32, adapted to be separately engaged by means of a set-screw, 33, on the bracket, 22.

The openings, 32, are spaced apart to correspond with diameters of the drum required for the marking of the usual sizes of strip-section for the intended use.

To prevent slip between the drum and 75 strip, we provide the respective segments, 6, with spurs, 34, adapted to engage the strip and cause the strip to positively rotate the drum as the strip is fed thereover.

In using the apparatus as described, the 80 strip is pulled from the reel, 3, over the drum either by the feed-movement of a sewing-machine or the like, or the hand of the operator, such feed-movement of the tape causing the drum to be rotated, and at each 85 complete rotation of the drum causing a mark to be made upon the strip by means of the pencil, 20, which marks will be equidistant for a given diameter of the drum.

For guiding the operator in adjusting of 90 the drum for different sizes, any known means may be employed for measuring the angular movement of the cam-disks, 12 and 13, relatively to the slotted segment-supporting disks, 9.

With the preferred form of spiral-groove which extends more than once around the circular extent of the cam-disks, some confusion might result from an indicating-scale and index-mark directly upon a cam-disk 100 and a segment-supporting disk.

To avoid this we prefer to 105 mount eccentrically upon the cam-disk, 13, an indicating gear-wheel, 35, having the usual size-numbers upon its face, adapted to be exposed one at a time through a sight-opening, 36, in the cam-disk, 13, or a cover-plate, 37, mounted thereupon, which gear-wheel, 35, meshes with a pinion, 38, in fixed relation to the neighboring segment-supporting disk, 9, whereby the angular or circular movement of the indicating wheel, 35, is less than the angular or circular movement of the cam-disk, 13, relatively to the segment-supporting disk, 9, in the operation of adjusting the drum to the desired size; and the ratio of the gear-wheel, 35, to the pinion, 38, is such that all the sizes for which the drum is adapted or intended can be exhibited within the single circular 115 extent of the wheel, 35.

In operation the strip 4 is drawn through the guide 5 by the feed movement of a sewing machine, the hand of an operator, or in any suitable manner. This drawing or advancing 125 of the strip 4 from the guide moves the strip 4 over the drum and as the drum is provided with spurs, the drum is rotated with the advancing of the strip. The periphery of the drum is adjusted to give the 130

required peripheral length so that various lengths of the strip 4 will be required to impart a complete revolution to the drum. The drum at each revolution brings the 5 notch 30 of the drum flange 28 opposite to or beneath the crayon support, and as soon as the notch reaches the support the spring 25 moves the crayon 20 against the strip and marks the same as the strip is fed for 10 wardly from the machine. The crayon 20 is again raised out of the notch 30 by the flange 28 and held in such position until the required length of strip 4 passes over the drum and imparts another complete revolution 15 to the same.

Various adjustments of the drum result in an increase or decrease of the peripheral length of the drum and consequently the 20 lengths of the strip 4 necessary to revolve the drum a complete revolution may be adjusted as desired.

What we claim as new and desirable to secure by Letters Patent is—

1. In a strip marker and in combination, 25 a drum, a holder for a marking device movable toward and from said drum, and means carried by said drum for inducing movements of the marking device toward the drum at regular intervals with relation to 30 the circular movement of the drum and for holding the marking device away from the drum at all other times.

2. In a strip marker and in combination, a drum, a marking device, a holder for said 35 marking device movable toward and from the drum, a cam carried by the drum, a cam follower carried by said holder and engageable with said cam, and means for adjustably varying the relative distance from the 40 drum of said cam follower and said marking device.

3. In a strip-marker and in combination, a drum having a plurality of expansible and contractible segments; means for securing 45 the segments in selected positions of adjustment; a marking-device; a holder for said marking-device movable toward and from the drum; a cam carried by the drum; a cam-follower carried by said holder engageable with said cam; and means for adjustably varying the relative distances from the 50 drum of said cam-follower and said marking device.

4. In a strip-marker and in combination, 55 a drum of variable diameter; a marking-device; a holder for said marking-device movable toward and from the drum; a cam carried by the drum; and a cam-follower adjustably mounted upon said holder in engagement with said cam whereby the normal 60 distance of the holder from the drum can be varied.

5. In a strip-marker and in combination, a pair of radially slotted end-disks adapted to rotate in unison with each other, one 65 having a peripheral cam; a plurality of drum-segments each engageable with oppositely disposed slots in the respective end-disks; a pair of cam-disks adapted to rotate in unison with each other concentrically 70 with, but independently of, said end-disks, said cam-disks being formed with oppositely disposed cam-grooves and said drum-segments having cam-followers engageable with the respective cam-grooves; releasable 75 means for securing said cam-disks and said end-disks together; a marking-device; a holder for said marking-device movable toward and from the drum formed by said segments; a cam-follower mounted on 80 said holder adapted to engage the peripheral cam on the end-disk; and means for adjustably varying the relative distance from the drum of said cam-follower and said marking-device. 85

6. In a strip-marker and in combination, a pair of radially slotted end-disks adapted to rotate in unison with each other, one having a peripheral cam; a plurality of drum-segments each engageable with oppositely disposed slots in the respective end-disks; a pair of cam-disks adapted to rotate in unison with each other concentrically with, but independently of, said end-disks, said cam-disks being formed with oppositely disposed cam-grooves and said drum segments having cam-followers engageable with the respective cam-grooves; releasable means for securing said cam-disks and said end-disks together, a marking-device; a holder for said marking-device movable toward and from the drum formed by said segments; a cam-follower mounted on said holder adapted to engage the peripheral cam on the end-disk; and a cam-follower adjustably mounted upon 100 said holder in engagement with said cam, whereby the normal distance of the holder from the drum can be varied. 105

7. A strip marker comprising a drum adapted to receive the strip and be turned thereby; a crayon supported at one side of the drum and adapted to engage the strip at each pre-determined advancement of the drum, and means for increasing and decreasing the peripheral length of the drum by adjustment of the drum itself to vary the distance between marks of the strip. 110

In testimony whereof, we have hereunto set our hands this 24th day of January, 1914.

JAMES J. SHERIDAN.
EDMUND S. STEVENS.
